Fig. 1

Fig. 2

Fig. 7

FIG. 1 is a perspective view of an expandable home trailer, showing our new design in expanded position;

FIG. 2 is a similar perspective view in closed position;

FIG. 3 is a front elevational view in expanded position;

FIG. 4 is a perspective view taken diagonally opposite FIG. 1.

FIG. 5 is a top plan view thereof;

FIG. 6 is a rear elevational view in closed position; and

FIG. 7 is an enlarged fragmentary sectional view taken on lines 7-7 of FIG. 5.

The horizontal band centrally disposed around the sides of the trailer is lined to represent color contrast. The evenly spaced lines around the door and roof edge represent ribs.

We claim:

The ornamental design for an expandable home trailer, as shown and described.
